ELECTRIC PULSE GENERATOR

Alec Harley Reeves, London, England, assignor
to International Standard Electric Corporation,
New York, N. Y., a corporation of Delaware

Application March 18, 1948, Serial No. 15,581
In Great Britain March 20, 1947

10 Claims. (Cl. 332—9)

1

The present invention relates to an electric pulse distributor or modulator circuit arrangement employing a cold cathode gas filled discharge tube.

The arrangement employs a discharge tube of the kind described in the specification of my co-pending U. S. application No. 14,184/48 filed March 11, 1948 for "Improvements in or relating to Electric Discharge Tubes."

An electric pulse distributing arrangement according to the invention comprises a cold cathode gas discharge tube having a sequence of discharge gaps, means for applying a potential to each of the gaps of sufficient magnitude to maintain a discharge thereacross, but insufficient by itself to initiate a discharge, means for applying a pulse to fire the first gap of the sequence, the arrangements being such that the remaining gaps are conditioned by ionisation migration to fire spontaneously in turn at one at a time, and means for deriving output pulses from the gaps.

In order to illustrate the invention, a specific application of the arrangement will be described, but the invention is not limited to this specific application, and may be adapted for use in other circumstances.

The invention will be described with reference to the drawing accompanying the provisional specification in which:

Fig. 1 shows a diagram of a pulse train which may be produced by the circuit arrangement according to the invention;

Fig. 2 shows a schematic circuit diagram of an arrangement according to the invention; and

Figs. 3 and 4 show minor modifications of Fig. 2.

The circuit arrangement of Fig. 2 is adapted to generate a pulse period modulated train of pulses for an electric communication system of the type described in the specification of U. S. application No. 756,262 filed June 21, 1947, for "Improvements in or relating to Multiplex Electric Communication Systems" by P. K. Chatterjee—A. H. Reeves. This type of train is illustrated in Fig. 1. From this figure it can be seen that the signalling time is divided into a number of equal signalling periods by a train of regularly repeated pulses 0 having some characteristic by which they may be distinguished from the channel pulses, such, for example, as a larger amplitude, as indicated in Fig. 1. Such pulses will be called "coded pulses" for convenience, and they do not carry any signal. Three successive coded pulses 0 are shown in Fig. 1. The chan-

2

nel pulses are initially generated as trains of pulses having a repetition frequency the same as that of the coded pulses and are interleaved so that in each of the above mentioned signalling periods each pulse belongs to a different channel. Four channel pulses designated 1, 2, 3 and 4 are shown in each of the two signalling periods which are shown in Fig. 1. The time positions of the channel pulses are varied by the corresponding modulating signals so that the time spacing between the pulse 1 of channel 1 and the preceding coded pulse 0 depends only on the instantaneous voltage of the signal carried by channel 1, and so that in the case of any channel pulse 2, the time spacing between that pulse 2 and the preceding pulse 1 depends only on the instantaneous voltage of the signal carried by channel 2, and so on. It will be understood, of course, that there may be any number of channel pulses in each signalling period.

In Fig. 1 the unmodulated positions of the channel pulses are shown by the dotted lines, and these positions should preferably be equally spaced between two successive coded pulses. The channel pulses 1, 2, 3, 4 are shown variously displaced in the signalling periods in accordance with the corresponding signal voltages.

The arrangement of Fig. 2 employs a multi-gap cold cathode gas filled discharge tube which as already stated is of the type described in the specification of co-pending U. S. Application No. 14,184/48. It comprises an anode 113 which consists of a long straight metal plate, and arranged opposite the anode are a plurality of similar metal cathodes consisting of short cylinders, and forming therewith a sequence of discharge gaps. These cathodes are equally spaced apart in a straight line and the first of them 114 is the starting cathode and the remainder are channel cathodes and are used for generating the channel pulses 1, 2, 3 etc. Only the first two and the last of these are shown and are designated 114A, 114B and 114N. It will be understood that there is one of these channel cathodes for each channel of the system. The channel cathodes are all equally spaced from the anode 113, but the starting cathode 114 is preferably placed rather closer to the anode.

The starting cathode is connected to ground through an adjustable resistance 115, and the channel cathodes are connected to ground through the secondary windings of corresponding transformers 116A, 116B etc. and 116N. Resistances 112A, 112B etc. and 112N are connected in series with these secondary windings as shown.

3

The primary windings of these transformers are connected to corresponding input terminals 117A, 117B, etc. and 117N to which the corresponding modulating signals are applied.

The anode 113 is connected through the primary winding of an output transformer 118 to the positive terminal 119 for the high tension source, the corresponding negative terminal 120 being grounded. The secondary winding of this transformer is connected through a network consisting of a series rectifier 121 and two shunt resistances 122 and 123 to a pair of output terminals 124 which are connected to the line or other medium over which the pulses are to be transmitted.

A master pulse generator 125 generates two trains of short negative pulses having the same repetition frequency, of 10,000 pulses per second, for example. The first of these trains comprises negative pulses of large amplitude (which will be called extinguishing pulses), and is applied through the blocking condenser 126 to the anode 113. The second train comprises negative pulses of moderate amplitude (called starting pulses) each of which occurs very shortly after the corresponding pulse of the first train and is applied over the blocking condenser 127 to the starting cathode 114. The master pulse generator 125 may be of any suitable known type and does not need detailed description.

The potential of the high tension operating source connected to terminals 119 and 120 should be insufficient to start a discharge between any of the cathodes and the anode, but should be capable of maintaining a discharge when it has been started. Then the circuit operates as follows:

It will be assumed that a negative extinguishing pulse has just been applied to the anode 113 and is of sufficient amplitude to extinguish any discharges which may exist between any of the cathodes and the anode. The negative starting pulse which immediately follows should be of sufficient amplitude to initiate a discharge between the cathode 114 and the anode 113. It is explained in the specification of the co-pending U. S. Application No. 14184/48, that under the proper conditions of gas pressure, electrode spacing and other factors, the presence of the discharge from the cathode 114 progressively lowers by ionisation migration the minimum striking potential of any other gap by an amount, and at a rate which depends among other factors on the distance between the two gaps. Thus for example, the striking voltage of the gap corresponding to the cathode 114A may be lowered by 80 volts more than that corresponding to the next cathode 114B is lowered. It follows that a short time after the discharge from the cathode 114 has struck, a discharge will occur from the cathode 114A, but not from any of the other cathodes, because the striking voltage will not have been lowered sufficiently since they are further away. However, the discharge from cathode 114A acts in exactly the same way on the striking voltage corresponding to the next cathode 114B, and a discharge takes place from that cathode. It will be clear that the same process continues, each gap being fired shortly after the preceding gap until the last cathode 114N is reached.

Hence since the various cathodes are equally spaced, the gaps will be fired in succession at substantially equally spaced intervals of time, as soon as the discharge from the cathode 114 has been struck by the starting pulse.

4

Each time a gap is fired, the anode current which passes through the primary winding of the transformer 118 increases abruptly by a constant amount, and since the transformer acts as a differentiating device, a train of short pulses of one sign will be produced in the secondary winding of the transformer, which should be poled so that these output pulses will pass through the rectifier 121 and can be obtained from terminals 114.

The firing of the gaps should be timed so that the last gap is fired before the arrival of the next extinguishing pulse which extinguishes all the gaps, and the tube is then ready for a fresh series 15 of operations which commences with the starting pulse which immediately follows. Since this extinguishing pulse cuts off the current through the primary winding of the transformer, a short pulse of large amplitude but of opposite sign to 20 the output pulses will be generated, and this is cut off by the rectifier 121. However, it might be useful to transmit this large pulse for synchronising purposes, for example, and in that case the rectifier 121 and resistances 122 and 123 could 25 be omitted.

It will be apparent that the above mentioned output pulses will comprise the coded pulses 30 of Fig. 1, derived from the starting cathode 114, and the channel pulses 1, 2, 3, etc., derived in 35 turn from the cathodes 114A, 114B, etc. and 114N.

The minimum striking voltage of any particular cathode such as 114B falls substantially uniformly with time when the preceding gap has 35 been fired. The corresponding gap will therefore be fired when the striking voltage has fallen to the potential of the high tension source. If, however, a modulating signal is applied to terminals 117B, a voltage will be produced in the secondary winding of the transformer 116B which 40 increases or diminishes the effective operating voltage applied to the corresponding gap. The discharge therefore occurs earlier or later than usual by an amount depending in magnitude and sign on the signal voltage. In other words, the 45 time interval between the striking of the discharges from the cathodes 114B and 114A is modulated in accordance with the signal, and so the time interval between the corresponding channel pulses 2 and 1 (Fig. 1) is likewise modulated. It 50 will be clear that all the other time intervals will be modulated in a similar way by the signals applied to the corresponding terminals 117.

It should be explained that the delay in the striking of the discharges from the cathodes is 55 believed to be principally due to the following circumstances:

(a) A small but finite time is necessary for the cathode glow which starts at the tip of the cathode to extend along the whole length of the cathode. Thus the lowering of the striking voltage of the adjacent gap which depends on the increasing numbers of ions and electrons produced takes time to develop.

(b) The ions and electrons formed in the first 60 gap take a small but finite time to drift into the neighbourhood of the second gap, and so their effect on the second gap is delayed.

This ionisation coupling which results from these two effects therefore has not, so to speak, 65 an infinitely steep leading edge, but increases progressively from zero, and so the resulting lowering of the striking voltage of the second gap increases with time in a finite and continuous manner.

70 For this reason it is possible to modulate the

striking time of the second gap within certain limits by an applied signal voltage in the manner explained.

The initial conditions for the striking of the discharge from the first cathode 114 may be conveniently adjusted by varying the resistance 115, which varies the rate of increase and final value of the corresponding current.

The gas mixture, pressure, and cathode gaps and spacings must of course be designed in accordance with the pulse spacings and time modulations desired. An example is given below of design details of a tube suitable for generating a pulse train according to the present invention. The repetition frequency of the coded pulses is assumed to be 10,000 pulses per second, and the time interval between any two adjacent pulses (Fig. 1) is assumed to be between 3 and 5 microseconds. The details of the tube and its operation are as follows—

Gas filling:

Neon	92%	Total pressure 100 mm. Hg.
Argon	1%	
Hydrogen	7%	

Electrode Material: Nickel cathode length

millimetres

Spacing between each pair of adjacent cathodes

millimetres

Gap between cathode 114 and anode do

millimetres

Gap between each of the other cathodes and anode

millimetres

Voltage of operating source

volts

Peak value of each cathode current

millamps

Duration of extinguishing pulse

microseconds

Amplitude of extinguishing pulse

volts

Duration of starting pulse microsecond

1

Amplitude of starting pulse

volts

With this tube, the extinguishing time for all the gaps will be about 10 microseconds, so the duration of the extinguishing pulse is chosen to be about double to give a good margin of safety.

While the tube shown in Fig. 2 has a flat straight anode plate and the cathodes are arranged in a straight line the anode could be curved, and take other forms than that of a plate, and the cathodes could be arranged in other ways.

An improved control may also be obtained by the use of an extra cathode providing an additional priming gap across which a discharge is permanently maintained. Such a priming gap should preferably be equidistant from the other cathodes, which therefore should be arranged in a circle with the extra cathode at the centre as shown diagrammatically, for example, in Fig. 3, which gives a plan view of a modification of Fig. 2. Elements not shown in Fig. 3 may be arranged exactly as in Fig. 2. The use of a permanently discharging priming gap is described in the specification of co-pending application No. 12086/47, now abandoned.

In this case the anode 113 consists of a circular metal disc, and the necessary number of cathodes 114 are arranged concentrically therewith, and with the proper spacing therefrom, as already explained. The extra cathode 128 is shown in the centre, and is connected through an adjustable resistance 129 and an additional voltage source 130 to terminal 120. The cathodes 114 are supposed to be connected as shown in Fig. 2.

The extra cathode is so spaced from the anode 113 that a discharge takes place permanently therefrom. The additional source is connected to augment the operating voltage for this cathode, and should be of such voltage that the discharge is not extinguished by the extinguishing pulse applied through condenser 126 to the anode 113.

By adjusting the current through the cathode 128 by means of the resistance 129, the general ionisation level of all the other cathodes may be varied. An increase in the general ionisation level has four principal effects on the other gaps:

- 15 1. A reduction of the minimum striking voltage;
- 2 2. A reduction of the difference between the striking and maintaining voltages;
- 20 3. A reduction in the minimum extinguishing time, and
- 20 4. An increase in the rate of spread of the cathode glow along each cathode when the discharge is struck.

Effect No. 3 is very useful as it is desirable to 25 reduce the extinguishing time in order to obtain the maximum channel space, and effect No. 4 is one factor which determines the relation between the signal voltage and the resulting time modulation, and can be used to adjust this relation.

30 Fig. 4 shows a slight modification of the arrangement of Fig. 3. The extra cathode 128 is provided with a corresponding extra anode 131 which is connected separately to the positive high tension terminal 119. The additional source 130 shown in Fig. 3 is then unnecessary, since the extinguishing pulses will not affect the extra anode. In Fig. 4 the anode 113 has been shown in the form of an annular disc, and the extra anode 131 is a centrally placed circular disc insulated from the anode 113. As in the case of Fig. 3, the ionisation level may be adjusted by means of the resistance 129.

35 In Figs. 3 and 4, the last of the channel cathodes 114N should be well separated from the starting cathode 114, as indicated, to prevent it from being appreciably affected by the ionisation from the starting gap, so that premature firing of the last gap is avoided.

40 By a slight modification, the arrangement shown in Fig. 2 may be adapted to operate as a pulse distributor for a multi-channel time-phase modulation pulse communication system, for example. In this case the transformer 118 may be omitted, the anode 113 being connected directly to terminal 119. After the application of the starting pulse to the cathode 114, the remaining gaps are fired in turn at regular intervals and each therefore generates a short pulse which may be obtained from the corresponding transformer 117A, 117B, etc. and 117N.

45 These transformers may therefore be connected to corresponding pulse time phase modulators (not shown) of conventional pattern instead of to the signal sources, and corresponding modulated trains of pulses may be obtained from these modulators properly timed for interleaving in the usual way. If desired the cathode 114 may be provided with a corresponding transformer (not shown) in order to obtain the coded pulses which define the signalling periods.

50 It will be clear, also that a distributor of this kind may be used to provide the gating pulses at the receiver of a multi channel time phase modulation system.

It will also be evident that the pulses generated by the tube shown in Fig. 2 may be produced if desired at various unequal intervals by spacing the cathodes 114 in a corresponding unequal manner.

What is claimed is:

1. An electric pulse modulator comprising a discharge device having a discharge gap, means for gradually lowering the resistance of said gap, means for applying a voltage to said gap while said resistance is being lowered to a value sufficient to cause said gap to fire when the resistance has reached a predetermined level, means for applying a signal voltage to said gap for varying the effective voltage on said gap and the time of firing thereof, and means responsive to the firing of said gap for deriving an output pulse.

2. A modulator according to claim 1, wherein said device is a gaseous discharge tube and said means for gradually lowering the resistance of said gap comprises means for gradually ionizing the gas in said gap.

3. A modulator according to claim 1, wherein said discharge device is a gaseous discharge tube and said means for gradually lowering the resistance of said gap comprising a priming discharge gap, means for firing said priming gap, said priming gap being arranged adjacent said first mentioned gap so that the ionization produced by the firing of the priming gap gradually migrates toward said first mentioned gap and gradually lowers its resistance.

4. A modulator according to claim 3, further including means for extinguishing said gap discharges.

5. A multichannel pulse modulation system comprising a discharge device including a plurality of successive discharge gaps arranged so that the resistance of each gap is gradually lowered upon the firing of its preceding gap, means for firing the first gap, means for applying a voltage to each of the other gaps while said resistance is being gradually lowered to a value sufficient to cause the firing of each of said other gaps at a predetermined time after the firing of its preceding gap, means for applying signal voltages of different channels to each of said other gaps to vary the effective voltage thereacross and their time of firing with respect to their preceding gaps, and means for deriving output pulses from the firing of said other gaps.

6. A multichannel modulation system according to claim 5, wherein said discharge device is

5 a gaseous discharge tube and said gaps are arranged adjacent each other so that the ionization produced by the firing of a given gap gradually migrates to the next succeeding gap and lowers the resistance thereof.

7. A multichannel pulse modulation system according to claim 5 in which all said other gaps have one electrode in common and said output pulses are derived from the common electrode.

8. A multichannel pulse modulation system according to claim 5 in which all said other gaps have a common anode, further including means for applying to said anode a negative pulse for extinguishing the gaps after the last one has fired.

9. A multichannel pulse modulation system according to claim 8, further comprising means for eliminating the extinguishing pulse from the output.

10. A multichannel pulse modulation system comprising a discharge device including a plurality of successive discharge gaps arranged so that the resistance of each gap is gradually lowered upon the firing of its preceding gap, means for firing the first gap, means for applying a voltage to each of the other gaps while said resistance is being gradually lowered to a value sufficient to cause the firing of each of said other gaps at a predetermined time after the firing of its preceding gap, means for applying signal voltages of different channels to each of said other gaps to vary the effective voltage thereacross and their time of firing with respect to their preceding gaps, and means for deriving output pulses from the firing of said other gaps, all said other gaps having one electrode in common, said output pulses being derived from the common electrode, and said means for deriving output pulses from the firing of said other gaps comprising an output transformer having its primary arranged in series with said common electrode.
